No. 880,506.

PATENTED MAR. 3, 1908.

S. I. CLAWSON.
FUME ARRESTER.
APPLICATION FILED MAY 20, 1907.

UNITED STATES PATENT OFFICE.

SELDEN I. CLAWSON, OF SALT LAKE CITY, UTAH.

FUME-ARRESTER.

No. 880,506.

Specification of Letters Patent.

Patented March 3, 1908.

Application filed May 20, 1907. Serial No. 374,743.

To all whom it may concern:

Be it known that I, SELDEN I. CLAWSON, a citizen of the United States, residing at Salt Lake City, in the county of Salt Lake and State of Utah, have invented certain new and useful Improvements in Fume-Arresters, of which the following is a specification.

This invention relates to fume arresters, and pertains especially to improvements upon my patent issued August 8, 1905, No. 796,956.

The object of this invention is to provide means revoluble in a body of water for carrying fumes through the water and for discharging the fumes laterally into the water below the top surface of the water.

A further object of the invention is to provide, in a fume arrester, a pair of pipes, one of which is revolved within the other for carrying fumes into a wheel revolubly contained in a body of water, and means for the exit of the fumes from such wheel into the water.

A still further object of the invention is to provide, in a fume arrester, a water-casing having a series of break-water vanes, a wheel in the water and carrying a fume-pipe, by which the fumes are conducted into the wheel, means carried by the wheel for discharging the fumes from the periphery of the wheel, and suitable means for revolving the wheel.

Various other objects, advantages and improved results are attainable by and through the special construction and arrangement of the parts of this apparatus.

In the accompanying drawings forming part of this application: Figure 1 is a side elevation of the apparatus. Fig. 2 is a vertical sectional view. Fig. 3 is a cross section on the plane indicated by the dotted line x—x Fig. 2. Fig. 4 is a detail perspective view of the fume-ring. Fig. 5 is a detail elevation of the fume-wheel.

The same reference numerals denote the same parts throughout the several views of the drawings.

A water-casing or tank 1, is secured to and supported by a frame 2, of any suitable or desirable form or construction, through which and a tank, a vertical shaft 3 extends to the bottom of the tank where the shaft is seated in a base-bearing 4. The shaft is provided with a pulley 5 driven by suitable power to revolve the shaft. A fume-pipe 6,

leads into a fume-pipe 7 through which the shaft extends, and said pipe 7 has an open end which projects into the water at a distance below the surface of the water so that the pipe 7 contains water up to the water level, or for a portion of its length.

The shaft has a fume-wheel 8 secured thereto and revolved in the water by the shaft directly under the open end of the pipe 7, so as to leave a passage 9 between the said pipe end and the top of the wheel. Secured to the wheel and extending into the pipe 7, between the latter and the shaft is a fume-pipe 10, which has its open end projected above the water. The pipe 7 is fixed or stationary and the pipe 10 is revolved in the pipe 7 by the shaft and the wheel.

The wheel 8 is preferably composed of disks 11, and a ring 12, having serrations 13. The disks are assembled to clamp the ring therebetween so that a portion of the ring projects beyond the periphery of the disks. The ring-opening and its contact disks form an annular fume-passage 14, from the pipe 10, to the serrated faces of the ring. The bottom of the wheel is provided with counterbalances 15, and the ring is clamped into position by bolts 15^a.

The tank 1 is provided with a series of break-water vanes 16, projecting radially from the tank so as to leave an interval or space between them and the periphery of the ring 12.

It will be seen that the fumes are drawn into the passage 14, by the revolution of the wheel, and discharged from said passage through the serrations of the ring; that the vanes 16, break or further agitate the water between the periphery of the ring and the tank so that the fumes may thoroughly mix or commingle with the water; and that the fumes pass through and from the wheel through both sides of the ring into the water, whence they are dispersed throughout the body of water.

It is obvious that only two wheel-disks may be employed for clamping the wheel therebetween; that the ring may be made integral with one of the disks; that the size and number of the vanes may be varied as desired, and that various other mechanical changes and equivalent construction and arrangement of the parts of the apparatus may be resorted to within the scope of this invention.

Having thus described my invention what I claim as new and desire to secure by Letters Patent is:—

1. In a fume-arrester, a fume-wheel having an axial fume-pipe leading into it, a ring carried by the wheel for discharging the fumes through the periphery of the wheel and forming an annular passage in the wheel from said pipe.
- 10 2. In a fume-arrester, the combination, with a suitable tank containing a body of water, a series of break water vanes within the tank, and the fume-pipes one within the other, of a fume-wheel revoluble in the water and having one of said pipes secured thereto for carrying the fumes from the other pipe into the wheel, and a serrated ring by which the fumes are carried out of the wheel.

3. In a fume-arrester, the combination, with a suitable tank containing a body of water, a pair of fume-pipes one revoluble within the other and both being partially within the water, and a driven shaft extending through said pipes, of a fume-wheel secured to the shaft below one of said pipes and having the other of said pipes attached and leading thereinto, and fume-passages from the revoluble pipe through the periphery of the wheel.

In witness whereof I hereunto set my hand in the presence of two witnesses.

SELDEN I. CLAWSON.

Witnesses:

MATHONIHAN THOMAS,
WILFORD MOYLE.
